UNITED STATES PATENT OFFICE.

GEORGE WILLIAM DAVIS, OF WESTMOUNT, QUEBEC, CANADA.

TYPE-WRITER-CARRIAGE CONSTRUCTION.

1,049,565.

Specification of Letters Patent.

Patented Jan. 7, 1913.

Original application filed January 3, 1907, Serial No. 350,637. Divided and application filed June 23, 1911, Serial No. 634,952. Divided and this application filed December 15, 1911. Serial No. 666,048.

To all whom it may concern:

Be it known that I, GEORGE WILLIAM DAVIS, of Westmount, in the district of Montreal, Province of Quebec, Canada, have invented certain new and useful Improvements in Type-Writer-Carriage Construction; and I do hereby declare that the following is a full, clear, and exact description of the same.

10 The object of this invention is to improve the construction of typewriter carriage frames. For full comprehension however of my invention reference must be had to the accompanying drawings forming a part 15 of this specification in which like reference characters indicate the same parts and wherein:

Figure 1 is a vertical transverse sectional view of the carriage supporting frame. Fig. 20 2 is a perspective view of the main frame and carriage supporting frame and the means detachably securing the latter to the frame; Fig. 3 is a perspective view of the frames of the main and vibratory carriages; 25 and Fig. 4 is a detail plan view of one end of the carriage and illustrating particularly the connection between the platen and the main carriage frame.

This application is a division of patent 30 application Serial No. 634,952, filed June 23, 1911, which is a division of patent application Serial No. 350,637, filed January 3, 1907.

The carriage supporting frame comprises 35 a pair of angular end frame pieces *d* and *e*, the ends of the vertical and horizontal legs of which have upper and lower connecting bars *f* and *g* respectively, secured thereto and constituting with the said end pieces an 40 intact carriage supporting frame.

The carriage consists of the main carriage frame and a vibratory carriage frame carried thereby, the platen roll 2 being mounted in the upper end of the vibratory 45 carriage.

The vibratory carriage consists of a pair of vertical end plates *q* rigidly yoked together at their lower ends by a rearwardly facing bar *r* of channel cross-section constituting a rail in which the shifting trundle roll *s* (constituting part of the shift mechanism not shown) of the carriage runs, the advantage of the rearwardly facing channel bar being that particles dropping

from the ink ribbon as it wears will not 55 lodge therein and clog the trundle roll.

In order to constantly maintain the linear area (in other words the area in which the line of writing is moved to use small type, capitals or figures and other characters) in 60 the same vertical plane the platen roll 2, which is supported upon the vibratory carriage, carries upon the trunnions at each end thereof sleeves *u* which are flattened at the sides at *v*, project through vertical 65 slots *w* in the end frame pieces *m* and *n* of the main carriage frame and slide within the slots thus maintaining the shifting movement of the vibratory carriage in a constant vertical plane. The upward displacement of the sleeves and trunnions is 70 limited by a removable strap *y*. The usual bar 3 carrying the ratchets 4, to one of which is connected the spring 5 for yieldingly maintaining the platen carrier in its 75 uppermost position, is carried by the carriage longitudinally thereof and according to this invention has a pair of lever arms 6 fixed rigidly at one end thereon as at 7 and having their opposite ends pivotally connected as at 8 to the lower parts of the end 80 frame plates *q* of the vibratory carriage.

What I claim is as follows:

1. In a typewriter the combination with the frame thereof, a main carriage supported movably thereon and having end frames the upper ends whereof are vertically slotted,—of a vibratory carriage carried by the main carriage and having end frames the upper ends whereof are formed with vertical 90 slots in alinement with and of less length than the vertical slots of the carriage, means movably connecting the vibratory carriage to the main carriage, a platen having a pair of trunnions projecting into the coinciding 95 slots of the main and vibratory carriages and resting in the slots of the latter, substantially as described and for the purpose set forth.

2. In a typewriter the combination with the frame thereof a main carriage supported movably thereon and having end frames the upper ends whereof are vertically slotted,—of a vibratory carriage carried by the main carriage and having end frames the upper ends whereof are formed with vertical 105 slots in alinement with and of less length than the vertical slots of the main carriage,

an oscillatory bar carried by the main carriage parallel to the oscillatory frame, a pair of arms mounted rigidly upon the bar and pivotally connected to the lower end of 5 the vibratory carriage, a coiled spring encircling the bar and connected at one end to the main carriage and at its other end to the bar, a platen having a pair of trunnions projecting into the coinciding slots of the main 10 carriage and vibratory carriage and resting in the slots of the latter, substantially as described and for the purpose set forth.

3. In a typewriter the combination with 15 a main carriage frame having vertical slots in its ends,—of a vibratory carriage frame carrying a platen roll with trunnions projecting through the said vertical slots, flattened sleeves carried by the projecting ends of the trunnions substantially as described 20 and for the purpose set forth.

4. In a typewriter the combination with 25 the main frame and a main carriage removably supported thereon,—of a vibratory carriage frame mounted upon the main carriage, means yieldingly maintaining the vibratory carriage in its uppermost position consisting of a spring actuated bar having a pair of radial arms pivotally connected to the vibratory carriage.

5. In a typewriter the combination with 30 the main frame of the machine,—of a carriage supporting frame comprising angular frame pieces one of the arms of each of which lie longitudinally of the machine near the rear thereof and are detachably secured thereto 35 the other arms being disposed vertically to the machine and transversely disposed bars connecting the corresponding ends of the arms of the angular frame pieces.

6. In a typewriter, the combination with 40 a main carriage frame having vertical slots in its ends,—of a vibratory carriage frame, a platen roll carried by the vibratory carriage and presenting trunnions which project through the said vertical slots and 45 sleeves upon the trunnions, such sleeves bearing between the adjacent ends of the main and vibratory carriage frames and being flattened to extend through the vertical slots, substantially as described. 50

In testimony whereof, I have signed my name to this specification, in the presence of two subscribing witnesses.

GEORGE WILLIAM DAVIS.
